UNITED STATES PATENT OFFICE

GEORGE M. McCANN, OF NEW CASTLE, DELAWARE

GUN

Application filed January 31, 1931. Serial No. 512,615.

(GRANTED UNDER THE ACT OF MARCH 3, 1883, AS AMENDED APRIL 30, 1928; 370 O. G. 757)

The invention described herein may be manufactured and used by or for the Government for governmental purposes, without the payment to me of any royalty 5 thereon.

This invention relates to improvements in guns.

In certain types of guns, the powder gases of discharge are conducted from the bore for 10 utilization in various mechanisms, for example, to check recoil, restore the gun to battery or unlock the breech block.

Where a gun of this character is equipped with a loose liner, that is, one in which a 15 radial play space provided between the liner and tube is taken up in firing and is restorable after firing and one in which the liner is free to expand and contract longitudinally when in action, it has been considered 20 essential to conduct the gases from the muzzle in order to preserve the integrality of the liner and tube.

I have discovered that the gas conduit may be carried by the liner intermediate its 25 length and that provision in the tube to allow for longitudinal movement of the conduit may be made without impairing the action of the liner or interfering with its removability from the tube.

To these and other ends, the invention 30 consists in the construction, arrangement and combination of elements described hereinafter and pointed out in the claim forming a part of this specification.

A practical embodiment of the invention 35 is illustrated in the accompanying drawings, wherein:

Fig. 1 is a sectional view of a gun with a removable liner equipped with a gas conduit;

Fig. 2 is an enlarged sectional view through the conduit;

Fig. 3 is a fragmentary plan view of the conduit.

Referring to Fig. 1 there is shown a gun 45 consisting of a tube 5 and a liner 6. The liner is freely insertable in the tube, preferably and usually from the rear, and is held against withdrawal by a ring 7 threaded 50 in the tube.

As shown most clearly in Fig. 2 there is a radial play space 8 between the liner and tube to facilitate insertion and withdrawal of the liner.

In this type of gun the powder pressure 55 acts in firing to dilate the liner into contact with the tube but the play space is restored when the powder pressure is no longer present.

In order to conduct the gases of discharge 60 from the bore for application to various mechanisms heretofore suggested there is provided a conduit 9 positioned intermediate the length of the gun. The conduit is inserted through a slot 10 in the tube and 65 threadedly secured in an aperture 11 in the liner. The length of the slot exceeds the diameter of that portion of the conduit passing therethrough so that the conduit may have relative longitudinal movement with 70 the liner without interfering with the tube. When the liner is to be withdrawn from the tube, the conduit is first removed.

I claim:

In a gun, an outer tube provided with a 75 slot, a liner within the tube and capable of longitudinal movement with respect thereto, a conduit insertable through the slot in the tube and attached to the liner, the diameter of the conduit being less than the 80 length of the slot in the tube.

GEORGE M. McCANN.
